UNITED STATES PATENT OFFICE.

EDWARD J. DRUDING, OF NEW YORK, N. Y.

BED.

No. 852,776.

Specification of Letters Patent.

Patented May 7, 1907.

Application filed December 4, 1906. Serial No. 346,206.

To all whom it may concern:

Be it known that I, EDWARD J. DRUDING, a citizen of the United States, and residing at New York, in the county of New York and 5 State of New York, have invented certain new and useful Improvements in Beds, of which the following is a specification, such as will enable those skilled in the art to which it appertains to make and use the same.

10 This invention relates to beds, couches, and the like; and the object thereof is to provide an improved mattress frame for articles of this class or to provide a frame for articles of this class having improved spring supports 15 for a mattress.

The invention is fully disclosed in the following specification, of which the accompanying drawing forms a part, in which the separate parts of my improvement are designated by 20 suitable reference characters in each of the views, and in which:—

Figure 1 is a perspective view of a bed provided with my improvement; Fig. 2 a plan view of a bed frame provided with my improvement and with the upright end members omitted; Fig. 3 a transverse section on the line 3—3 of Fig. 2; Fig. 4 a plan view of a buckle device which I employ; and, Fig. 5 a bottom plan view of a hook which I also employ.

In the drawing forming part of this specification, I have shown at *a* a bed or mattress frame comprising parallel end members *a*² and parallel side bars or members *a*³.

35 In the form of construction shown, the bed or mattress frame is provided with upright end members *a*⁴, but it will be understood that the said end members are not necessary in the construction of a couch or lounge, and 40 may or may not be employed in the construction of a bed, all that is necessary in either event is to provide suitable legs or supports for the bed or mattress frame, and in the form of construction shown, the upright members *a*⁴ form such legs or supports.

In the practice of my invention, the parallel side bars or members *a*³ are composed of separate telescopic or longitudinally adjustable parts, one of which slides within the other as 50 clearly shown in Fig. 3, one of said parts is provided with equally spaced holes *a*⁵ and the other with one or more corresponding holes *a*⁶, and the separate parts are connected by bolts or similar devices *a*⁷ adapted to be 55 passed through said holes.

In the form of construction shown, the separate parts of the parallel side bars or members *a*³ of the bed or mattress frame are composed of angle-iron as shown in Fig. 3, and this is the form of construction which I 60 prefer, the parallel end members *a*² of the bed or mattress frame being also composed of similar material, in order to facilitate the connection therewith of the spring members of the bed or mattress frame as hereinafter described.

The spring members or supports of the bed or mattress frame consist of flexible straps *b* preferably of textile material, and said members are extended, in the form of construction shown, longitudinally of the bed or mattress frame and are connected with the end members *a*² thereof at one end by spiral springs *c* and at the opposite end by means of straps *d* having buckle attachments *d*² and 75 hook attachments *d*³.

The springs *c* are provided with hooks which are passed through holes *e* in one of the end members *a*² of the bed or mattress frame and the corresponding ends of the strap devices *b* are provided with link members *f* with which said springs are connected. The opposite ends of the strap members *b* are connected with the buckles *d*² in the usual or any desired manner, and the hook members *d*³ 85 are connected with the corresponding end bars or members *a*² of the bed or mattress frame by being passed through holes *g* formed therein.

By means of the buckle and strap devices *d* 90 the lengths of the flexible straps *b* may be regulated, as will be understood, and by means of the telescopic construction of the side bars or members *a*³ of the bed or mattress frame, the said bed or mattress frame, 95 or the length thereof may also be adjusted, and in this way, I provide a bed or mattress frame the length of which may be adjusted, as desired, and said bed or mattress frame may thus be made to suit any possible requirements as to length.

In the drawing forming part of this specification, I have shown the spring straps or devices *b* as running longitudinally of the bed or mattress frame only, but it will be understood that similar devices may be placed transversely to said frame if desired, but it will not be necessary for the last named spring straps or devices to be adjustable as to length.

Having fully described my invention, I 110

claim as new and desire to secure by Letters Patent, is:—

A bed or mattress frame, the side bars of which are composed of separate parts where-
5 by the length thereof may be adjusted longitudinally, said frame being also provided with longitudinally arranged main straps for supporting a mattress, said main straps being connected with one end of the frame by
10 means of spiral springs and with the other end of the frame by means of supplemental straps provided at one end with buckles

through which the main straps are passed and at the other end with hooks which en-
gage said end of the frame.

In testimony that I claim the foregoing as my invention I have signed my name in presence of the subscribing witnesses this 1st day of December 1906.

EDWARD J. DRUDING.
